ATTORNEY.

UNITED STATES PATENT OFFICE.

ROBERT B. HOUGH, OF ERIE, PENNSYLVANIA, ASSIGNOR TO THE HOLLANDS MANUFACTURING COMPANY, OF SAME PLACE.

DESIGN FOR A WRENCH-JAW.

SPECIFICATION forming part of Design No. 29,338, dated September 13, 1898.

Application filed July 15, 1898. Serial No. 686,042. Term of patent 14 years.

To all whom it may concern:

Be it known that I, ROBERT B. HOUGH, a citizen of the United States, residing at Erie, in the county of Erie and State of Pennsylvania, have invented a certain new and original Design for Wrench-Jaws; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

The leading feature of my design for a wrench-jaw consists, substantially, in the form of the jaw and embodies a jaw having its face serrated with a screw-threaded shank or stem thereon, having its sides cut away and provided with concave recesses so located that the lower portion of the shank or stem is much wider than the upper portion thereof, thereby providing for strength and maximum lightness.

In the drawings, Figure 1 shows a perspec-

tive view of my wrench-jaw. Fig. 2 is a top 25 or plan view of the same. Fig. 3 is an end view of the same.

In the illustrations, A is the face of the jaw, provided with serrations *a*, and B is the shank or stem of the jaw, the sides of which 30 are cut away, and its upper and lower faces B' and B² are provided with screw-threads *b* and *b'*, and the lower face B² is approximately one and one-half times the width of the upper face B', so as to provide for strength at that 35 point. The sides of the shank or stem B are provided with concave flutes C C, which extend around into the sides of the jaw portion A, which serve to lighten it.

What I claim is—

The design for a wrench-jaw, substantially 40 as shown and described.

In testimony whereof I affix my signature in presence of two witnesses.

ROBERT B. HOUGH.

Witnesses:

FRED EINFELDT,
H. J. CURTZE.
